HJALMAR CARLSON, OF DULUTH, MINNESOTA.

TRACK-LAYING MACHINE.

1,027,373.

Specification of Letters Patent.

Patented May 21, 1912.

Application filed February 23, 1909. Serial No. 479,536.

To all whom it may concern:

Be it known that I, HJALMAR CARLSON, a citizen of the United States, residing at Duluth, in the county of St. Louis and State 5 of Minnesota, have invented certain new and useful Improvements in Track-Laying Machines, of which the following is a specification.

My invention relates to improvements in 10 track-laying machines, and has for its object the provision of a machine of this character of the automobile class, which, provides its own track or runways, and serves the purpose of a compact and efficient machine 15 for supporting and moving devices as hoisting machinery, derricks, shovels, or other implements, thus producing a compact and self-contained implement for the purpose.

20 The invention consists essentially of a platform supported upon suitable trucks and wheels, the latter moving over a pair of endless rails, which are connected to a series of supporting ties. And it further 25 consists in certain novel features of construction and combination and arrangements of parts for actuating and operating the propelling means of the machinery of the device, and also means for steering the implement.

30 In the accompanying drawings I have illustrated one example of the physical embodiment of my invention constructed according to the best mode I have so far devised for the practical application of the principles.

Referring to the drawings which form a part of this specification, and in which similar reference numerals indicate like 40 parts, Figure 1 is a broken plan view of the machine, with platform and steering mechanism removed. Fig. 2 is a broken vertical section of the machine on line 2—2 Fig. 1. Fig. 3 is a broken vertical section of the machine on line 3—3 Fig. 1. Fig. 4 is a detail plan view of the steering mechanism. Fig. 5 is a plan view of one of the cross ties, upon which the implement is supported, showing the jointed portion of a rail at one 45 end; portion of the propelling chain in the center, and the device for holding the rail in place at the other end of the tie. Fig. 6 is a sectional view on line 6—6 Fig. 5. Fig. 7 is a vertical section the section being taken as on line 7—7 Fig. 5. Fig. 8 is a

sectional view, showing in detail the adjustable support for the sprocket wheels. Fig. 9 shows the bent portion of a supporting stanchion illustrated in Fig. 8. Fig. 10 is a side elevation of one of the rail joints. 60 Fig. 11 is a section on line 11—11 Fig. 10. Fig. 12 is a section on line 12—12 Fig. 10. Fig. 13 is a side elevation of the reverse side of rail joint shown in Fig. 10, and Fig. 14 is a perspective view of a rail joint. Fig. 65 15 is an enlarged detail longitudinal sectional view of a portion of a tie, showing the spring pressed detent for locking the members together.

The platform 1 should be of suitable 70 strength to support a derrick, shovel, or other implement, and is supported preferably upon double trucks 2, 2. The axle 3 of one of these trucks may have connected thereto motive power in the form of an 75 electric motor, gas engine, or the like, or may be connected to an engine carried on the platform 1, (not shown).

At each end of the car platform 1 a yoke or stanchion 5 is suspended, and upon the 80 lower outermost cross bar 6, a bracket 7 is supported. Each bracket 7 has journaled therein a sprocket wheel 8, over which passes the sprocket chain 9, which, as clearly shown in Fig. 3 is propelled by fingers or 85 prongs 10 formed on the gear wheel 11. The wheel 11 is flexibly supported by means of shaft 12, between the pivoted frame 13, one end of which has the shaft 12 journaled therein and its other end being pivoted on shaft or axle 3, and arm of hook 14, which is connected to a bolt 15 in the frame or platform, by means of a spring 16. The gear wheel 11 is in mesh with a driving gear wheel 17 on shaft 3, and the flexible support of shaft 12 permits play or adjustment to changing conditions when the machine is moving over uneven ground. 90 95

The propelling chain may be tightened or slackened by means of the device more 100 clearly illustrated in Fig. 8. As shown in said figure, the sprocket wheels 8 are movable longitudinally of the machine through the medium of their brackets 7. The brackets are movably supported on the surface of the bar 6 of the stanchion 5, and a screw 18 is threaded into a hole 19 in the bracket and its shoulder or collar 20 bears against a perforated lug 21 formed on the bar 6. If required a spring 22 may be in- 110

terposed between lug 21 and a head 23 of the screw to act as a buffer, and the bracket may be moved away from or toward the machine by turning the screw, as will be understood.

5 From the above description it will be evident that the two stanchions 5 support the adjustable brackets and idler sprocket wheels over which travel the propelling 10 sprocket chain, and that the chain is caused to travel through the medium of motive power applied to shaft or axle 3, gear wheels 17, 11, and fingers or prongs 10, the latter engaging the links of the chain.

15 The chain 9 carries a series of sectional cross ties 24, and a section of each tie is rigidly and firmly secured to the chain. Thus the tie comprises two end sections or pieces 25 and an intermediate portion 26. The intermediate portion 26 of each tie is formed 20 with two parallel side bars 27, 27 each of which is rigidly secured to the chain 9 as indicated at 28, and the end pieces are provided with side tongues 29 adapted to slide 25 in and out in the grooves 30 in bars 27. A spring 31 with a detent 32 is secured to the end sections. The detent projects through a hole or perforation 33 in the end section, and, when the sections are in position to be 30 locked, also projects into an inclined groove 34 in the intermediate section, thus limiting the outward movement of the sections. As the end sections are brought toward each 35 other, the detent 32 rides up on the bottom of this groove, being held in spring pressed contact therewith, which releases the locked joint between the intermediate and end pieces at the initial movement of the end piece toward the center of the tie.

40 As clearly shown in Fig. 1 there are two endless sectional rails, upon which the wheels of the trucks travel. These endless rails are made up of sections or pieces 35 jointed together so that they may travel 45 around the guide wheels 36, pivoted at 37 in the yokes or stanchions 5.

The joints of the rails are clearly illustrated in Figs. 10, 11, 12, 13 and 14. The web of one end of each section 35 is cut away 50 at 38 in order to receive the shuttle piece 39, which is slidable therein and at its outer end is fashioned into a hook 40. The hook 40 is positioned to partially surround a post 41 formed between the head and base of the adjacent section 35, and offset from the line of 55 the web, as clearly seen in Fig. 12. The joint is flexibly connected to the end sections of the cross ties by means of the post 42 which is embedded loosely so that it may 60 swivel in the tie and is provided with ears 43 at its upper end for connecting the bolt 44. The shank of the post 42, as seen in Fig. 7, is embraced by a yoke 42^a mounted, as at 42^b, as seen clearly in Fig. 5. This bolt 44 is formed with an eye 45 surrounding

the post 41 of a rail section, and the shuttle piece 39 is cut away or slotted at 45' to permit movement of the eye bolt. The manner of embedding post 42 in the tie avoids any danger of the eye 45 being torn off as the sections of the rail pass around the wheels 36. The joint of the rail sections is made continuous preferably by the adjoining ends formed with the overlapping piece 46 and underlapping piece 47 of the rail heads. 75 Thus the continuous sectional rails are flexibly secured, at their joints to the movable end sections of the sectional cross tie, and movement of the continuous rails around their guide wheels at the ends of the machine is effected. Preferably wheels 36 are formed with cut away corners or recesses 48, to receive the post 41 of each rail joint as said joint passes around the wheel. In this manner the rails 35 are held in engagement 80 with the wheels as the ties pass around the ends of the apparatus. To facilitate the movement of the rail sections at their turning points, the cross ties may be provided with rollers 49 over which the sections may 85 move as they turn on the wheels 36.

In operating the machine it may be found necessary to steer the same, and provision is made for this requirement in the following construction. Each stanchion 5 is pivoted to the car platform, and is movable on its pivot, the mechanism being duplicated at each end of the car, so that the description of one device applies to both. The stanchion 5 is provided with an upright post 50 which is loosely journaled in a head 51 formed integral with the pivoted bracket 52. This bracket 52 is pivoted at 53 to the car platform and has journaled therein the post 54 of a hand wheel 55, a rack wheel 56 being 100 fixed to the lower end of the post. This rack wheel is adapted to engage the segmental rack bar 57 which is rigidly fastened to the car platform. Thus by turning the hand wheel the bracket is swung on its pivot 105 either to the right or left (Fig. 4) and as the bracket carries with it the stanchion, said stanchion likewise carries with it the propelling chain and endless tracks with their series of cross ties.

115 The *modus operandi* of the machine is as follows: Assuming the driving shaft properly driven, the train of gears operates the connections to propel the driving chain 9 over the idler sprocket wheels at each end of the machine. The chain carries with it the attached cross ties, which in turn are connected at the joints to the sectional rails and thus carry the rails. Assuming the machine to be traveling toward the left in Fig. 1, the 120 cross ties on the upper side of the chain 9 are turned upside down and moving forward, as are also the portions of the rails adjacent the upper side of the chain. When the ties are upside down the end sections 125

thereof are drawn in toward the center of the tie, but as the joint of the rail engages the guide wheel at the front of the machine, the sliding end sections are carried outwardly by reason of the rail passing around the guide wheels, and as the chain 9 passes down over the idler sprocket, the end sections are moved to their outermost positions and said movement is limited by the spring 5 detents as described. The tie thus described remains on the ground, and stationary, until the machine has moved a distance equal to its length, when said tie is caused, by chain 9, to rise at the rear of the machine, and the chain turns the tie upside down again, and its continuous movement is effected toward the front of the machine. The ties are thus continuously laid down in front of the machine and picked up at the rear as the machine travels forward.

10 The cross ties are preferable constructed of iron, and the length of the tie will be governed by the gage of the track required, but of course the intermediate portion of the tie must be within the lines of the flanges of the truck wheels. The propelling chain must of course be of sufficient strength to manipulate the endless track way, and these features are properly worked out to suit 15 different conditions of service.

20 From the above description taken in connection with the drawings it is evident that I have produced a machine which fulfills all the conditions set forth as the purpose 25 and object of my invention.

25 Slight changes or minor modifications may be made in the construction and assemblage of the elements of the machine, but such colorable changes I consider within the 30 scope of my claims.

35 Having thus fully described my invention, what I claim as new and desire to cover by Letters Patent is:—

40 1. The combination with a pair of jointed endless tracks and guide wheels therefor, of a series of cross ties connected to the joints of said track, a frame supporting the tracks, and propelling means, supported in said frame, for actuating the tracks to lay 45 down the cross ties at the front of the machine and pick them up at the rear thereof.

45 2. The combination with a pair of sectional endless tracks, a series of cross ties attached thereto, and guiding means for 50 said tracks, of a pair of wheeled trucks on the rails, a platform on the trucks, a frame suspended from the platform, and propelling means for actuating said tracks to lay the cross ties at the front of the machine and 55 pick them up at the rear.

60 3. The combination with a pair of jointed endless tracks and means for guiding them, of a propelling medium, and sectional cross ties connected to said propelling medium and tracks.

4. The combination with a platform supported upon wheeled trucks, of a propelling chain suspended therefrom, cross ties rigidly attached to said chain, a pair of endless sectional trackways loosely connected to said cross ties, and means operated from one of the wheeled trucks for actuating said propelling chain.

5. The combination with a platform supported upon wheeled trucks, movable suspending frames on the platform and a propelling chain operatively supported in said frames, cross ties rigidly attached to said chain, a pair of jointed endless trackways loosely connected to said ties, and means operated from one of said trucks for actuating the propelling chain.

6. The combination with a movable platform, supporting frames thereon, and a propelling chain suspended from said frames, sectional cross ties portions of which are rigidly attached to said chain, a pair of jointed endless trackways the movable portions of said sectional ties attached to said tracks at the joints; and means for actuating said propelling chain.

7. The combination with a movable platform of a pair of movable stanchions suspended therefrom, means for swinging said stanchions on a pivot, a propelling chain suspended in said stanchions, cross ties rigidly connected to said chain, and endless trackways connected to said ties.

8. The combination with a platform and its wheeled trucks, of a propelling chain supported from said platform, actuating means flexibly supported from the platform and engaging said chain, said actuating means being operated from the truck, and a continuous trackway operatively connected to the propelling chain.

9. The combination with a propelling chain and means for actuating it, of a series of sectional cross ties portions of which are rigidly attached thereto, a pair of endless jointed trackways and the joints of the tracks connected to the cross ties, said ties having rollers thereon to facilitate the travel of the trackways.

10. The combination with a propelling chain and means for actuating it, of a series of cross ties rigidly attached thereto, movable end pieces forming parts of the ties, and a pair of endless sectional trackways loosely connected to said end pieces.

11. The combination with a propelling chain and means for actuating it, of a series of cross ties rigidly attached thereto, movable end pieces forming portions of the ties and means for locking said pieces to the ties in extended positions, and trackways connected to said ties.

12. The combination with a propelling chain and means for actuating it and a series of cross ties attached thereto, of movable

- end pieces forming parts of said ties and means for locking said portions together, and jointed tracks connected to said end pieces, the connection being formed at the 5 joints in the tracks.
13. The combination with a propelling chain and means for actuating it, cross ties rigidly attached to said chain, and movable end pieces forming parts of said ties, of 10 a pair of jointed endless tracks loosely connected at said joints to said movable end pieces, and guide wheels over which said tracks travel, whereby the end pieces are moved in and out relatively toward the propelling chain.
14. The combination in a jointed track as described of sections one of which is formed with a post, a movable member having a hook around said post and loosely connected 20 to the other section, and the heads of the

adjoining rail sections over and underlapping each other.

15. The combination with a propelling chain and means for actuating it, cross ties rigidly attached to said chain and movable 25 end pieces forming parts of said ties, of a pair of jointed endless tracks loosely connected at their joints by a universal connection to said end pieces, and guide wheels over which the tracks travel, whereby the 30 cross ties are laid upon the ground at the front of the machine and picked up at the rear continuously.

In testimony whereof I affix my signature, in presence of two witnesses.

HJALMAR CARLSON.
